P. F. ROGERS,
LUBRICATING GREASE CUP,
APPLICATION FILED AUG. 8, 1916.

Patented Oct. 9, 1917.

By

H. A. Rogers, Attorneys.

UNITED STATES PATENT OFFICE.

PERLEY F. ROGERS, OF BARTLETT, NEW HAMPSHIRE.

LUBRICATING GREASE-CUP.

1,242,477.

Specification of Letters Patent.

Patented Oct. 9, 1917.

Application filed August 8, 1916. Serial No. 113,773.

To all whom it may concern:

Be it known that I, PERLEY F. ROGERS, a citizen of the United States, residing at Bartlett, in the county of Carroll and State 5 of New Hampshire, have invented certain new and useful Improvements in Lubricating Grease-Cups, of which the following is a specification.

This invention contemplates an improved 10 lubricating grease cup and has as its primary object to provide a device of this character wherein the cap of the cup will be adjustable for forcing grease out of the cup and wherein the said cap will be yieldably 15 held at adjustment.

The invention has as a further object to 20 provide an improved locking member arranged to coact with the cup shank for holding the cap of the cup at adjustment and 25 wherein the said locking member can be detached from the said shank only in a certain position of the locking member with respect to the shank so that the said locking member will not likely become lost or 30 placed.

And a still further object of the invention 35 is to provide a cup of the above described character adapted for general application and use.

Other and incidental objects will appear 40 as the description proceeds and in the drawings wherein I have illustrated the preferred embodiment of the invention and wherein similar reference characters designate cor- 45 responding parts throughout the several views:

Figure 1 is a side elevation partly broken away and particularly showing the internal construction of the cup,

Fig. 2 is a side elevation showing the manner in which the locking member for the cap of the cup is arranged to yieldably 50 coact with the shoulders upon the cup body in holding the cap at adjustment,

Fig. 3 is a similar view showing the connection between the locking member and the cap,

Fig. 4 is a sectional view showing the sockets carried by the cup body to coact 55 with the locking member, the locking member being detached,

Fig. 5 is a sectional view more particularly showing the construction of the body of the locking member, and

Fig. 6 is a detail perspective view of the locking member.

In carrying out the invention, the cup is provided with a body 10 having an externally screw threaded stem 11 connected with the body by a reduced shank 12. The body 60 10 is internally formed preferably with a frusto-conical grease chamber 13 and adjacent its upper extremity, is externally screw threaded to adjustably receive a cap 14. Surrounding the stem 11, at the lower extremity of the shank 12 is an annular shoulder 15 confronted by a similar shoulder 16 65 at the upper extremity of the said shank, the shoulder 16 being formed by the lower end of the body 10 of the cup. Formed in 70 the inner face of the shoulder 15 are a plurality of radially extending grooves or sockets 17 quadrantly spaced about the shank 12 and which communicate at their inner extremities, with radial recesses 18 formed in 75 the said shank. The cup may, of course, be constructed any desired size and the shank 11 thereof may be varied in diameter as occasion may demand so that the cup may be readily mounted by the said stem in active 80 position. Leading from the grease chamber 13 of the body 10 through the stem and through the shank 12, is a suitable channel 19 through which the grease from the said chamber may flow and in this connection, it 85 will be observed that the cap 14 may be adjusted upon the body 10 of the cup for forcing the grease out through the stem.

Arranged to hold the cap 14 at adjustment, is a locking member or element shown 90 in detail in Fig. 6 of the drawings. This locking member is preferably formed from suitable resilient sheet metal and includes an arcuate body 20 of a radius to freely receive the shank 12 of the cup and fit around the 95 said shank in the manner illustrated particularly in Fig. 5. The body 20 is of an arc greater than a semi-circumference so that the distance between the free ends of the said body is less than the diameter of the 100 shank 12. At one end, the body 20 is cut away to provide an upwardly directed spring tongue 21 terminating at its outer extremity in a shoulder 22 while the opposite end of the said body is cut away to provide a shoulder 23. Projecting laterally from the body 20 adjacent the inner extremity of the tongue 21, is an upwardly directed arm 24 and from the said arm, the body 20 is bent longitudinally toward its outer extremity to provide an upwardly bowed 105 spring 25. Adjacent its outer end, the body 110

is bent or otherwise provided with a shoulder or rib 26. The arm 24 is arranged to extend longitudinally of the cap 14 as particularly seen in Figs. 2 and 3 of the drawings and is freely received by an eye or loop 27 carried by the cap.

It will now be observed that the body 20 is arranged to seat adjacent its inner extremity upon the upper face of the shoulder 15 with the spring 25 yieldably bearing between the shoulders 15 and 16 for urging the rib 26 to coöperate with the shoulder 15 and selectively engage within the sockets 17. At the same time, the spring tongue 21 will yieldably engage the shoulder 16 for holding the body 20 against lateral rocking movement between the shoulders 15 and 16 against the tension of the spring 25. Upon rotation of the cup 14, the body 20 of the locking member will be caused to ride around the shank 12 by the arm 24 with the arm sliding within the loop 27 of the cap as the cap is screwed down. Upon the adjustment of the cap, the rib 26 will be urged by the spring 25 of the body 20 of the locking member to yieldably engage within one of the sockets 17 for holding the said cap at adjustment. Since the distance between the shoulders 22 and 23 of the body 20 of the locking member is less than the diameter of the shank 12 of the cup, the locking member will normally be held against displacement so that the said locking member will not, under normal conditions, become detached or lost.

However, particular attention is now directed to the arrangement whereby the said locking member may be detached from the shank 12 when desired. To effect this result, the shoulder 23 of the body 20 of the locking member is moved to a position opposite one of the recesses 18 in the shank. The arm 24 is then shifted to pivot the body 20 upon the said shoulder away from the shank 12, the shoulder 23 being thus caused to enter the said recess so that the shoulder 22 may then ride around the shank to free the locking member. In this connection, it will be observed that the distance between the inner extremity of one of the recesses 18 and the periphery of the shank 12 opposite the said recess is equal to the distance between the shoulders 22 and 23 so that when the shoulder 23 is disposed within one of the said recesses, as just above set forth, the shoulder 22 will freely ride around the shank so that the locking member may thus be easily disconnected. The locking member is, of course, attached to the shank 12 in a similar manner. However, it is to be observed that the said locking member can be detached from the shank only when the said member is shifted to occupy a certain position with respect to the shank so that the possibility of the said

locking member becoming accidentally displaced is reduced to a minimum.

Having thus described my invention, what I claim and desire to secure by Letters Patent is:

1. A lubricator cup including a body provided with a shank, spaced shoulders carried by the shank, a cap adjustable upon the body, and a locking member having a body embracing the shank to bear between said shoulders with the said locking member engaging the cap for holding the cap at adjustment. 70

2. A lubricator cup including a body provided with a shank, spaced shoulders carried by the shank, a cap adjustable upon the body, and a locking member having a body embracing the shank and bowed to yieldably bear between the said shoulders with the said locking member engaging the cap for holding the cap at adjustment. 80

3. A lubricator cup including a body provided with a shank and having spaced shoulders formed thereon, a cap adjustable upon the body, and a locking member having a body rotatable about the shank and bowed longitudinally to provide a spring bearing between the said shoulders upon one side of the shank, and a tongue carried by the body to yieldably bear between said shoulders upon the opposite side of the shank against the tension of said spring with the locking member engaging the cap for holding the cap at adjustment. 90

4. A lubricator cup including a body provided with a shank and having spaced shoulders formed thereon with one of said shoulders provided with a socket, a cap rotatably adjustable upon the body, and a locking member having a body rotatable about the shank and engaging the cap with the said body bearing between the said shoulders and provided with a shoulder to engage within said socket for holding the cap at adjustment. 100

5. A lubricator cup including a body provided with a shank and having spaced shoulders formed thereon, a cap rotatably adjustable upon the body and provided with a loop, and a locking member including a body rotatable about said shank to bear between said shoulders, and an arm freely received by said loop for holding the cap at adjustment. 115

6. A lubricator cup including a body provided with a shank and having spaced shoulders formed thereon, a cap rotatably adjustable upon the body, there being a recess formed in the shank, and a locking member including a body having confronting ends and formed to rotatably embrace the shank and bear between the said shoulders with the locking member operatively engaging the cap for holding the cap at adjustment, the distance between the ends 120

of the body of the locking member being less than the major thickness of the said shank and the body of the locking member being movable to position one end thereof in 5 said recess for disconnecting the locking member from the said shank.

7. A lubricator cup including a body provided with a shank, a cap rotatably adjustable upon the body, and a locking member 10 engaging the cup and including a body having confronting ends and formed to rotatably embrace the shank with the locking member acting to hold the cap at adjustment, the distance between the ends of the 15 body of the locking member being less than the major thickness of the said shank.

8. A lubricator cup including a body provided with a shank, spaced shoulders associated with the shank, a cap adjustable upon 20 the cup, and a locking member including a body rotatably connected to the shank between said shoulders and provided with an upstanding arm operatively engaging the cap, the body upon one side of said arm be-

ing bowed to engage between said shoulders 25 and upon the opposite side of the arm being formed to provide a tongue coacting with the said shoulders against the tension of the bowed portion of the body for holding the cap at adjustment. 30

9. A lubricator cup including a body member, a cap member rotatably adjustable upon the body member, one of the said members being formed with a shank, a locking element including a body loosely mounted 35 upon said shank, and an arm, and a loose connection between the said arm and the other of said members for holding the locking element fixed against rotary movement with respect thereto with the body of the 40 locking element operable to coöperate with the shank carrying member for holding the cap at adjustment and with the said arm slide longitudinally with respect to said connection as the cap is adjusted. 45

In testimony whereof I affix my signature.

PERLEY F. ROGERS. [L.S.]
